JOHN T. VOIGT, OF RICHMOND BEACH, WASHINGTON.

GOLD-SAVING MACHINE.

1,160,550.

Specification of Letters Patent.

Patented Nov. 16, 1915.

Application filed October 22, 1914. Serial No. 867,940.

To all whom it may concern:

Be it known that I, JOHN T. VOIGT, a citizen of the United States, residing at Richmond Beach, in the county of King and State of Washington, have invented certain new and useful Improvements in Gold-Saving Machines, of which the following is a specification.

This invention relates to ore concentrators or amalgamators.

The object is to produce an economically constructed and efficient device of this character for the saving of the finest float-gold, for scouring particles of quartz and for separating and saving the precious metals from the tailings of quartz-mills.

The invention consists in the novel construction and combination of parts, as will be hereinafter described and claimed.

In the accompanying drawings, Figure 1 is a longitudinal vertical section of apparatus embodying the present invention. Fig. 2 is an end elevation of the ore distributer shown detached. Fig. 3 is a like view of the rotary feeder.

In the drawings, 5 designates a substantially cylindrical drum which is preferably constructed of a circular head 6 and two spaced rings 7 and 8 which serve with the head to support interposed annular copper plates 9 and 10. The plate 9 is desirably of less width than the other plate. Provided in the head and rings are rabbets 12 for the reception of the ends of said plates and, to prevent any leakage at such joints, rabbets 11 are provided exteriorly of the plates to receive packings 13. Said rings are also provided with ribs 7¹ and 8¹ to protrude within the inner peripheries of the plates to afford relatively shallow peripheral recesses A and B within the drum. The ribs 7¹ and 8¹, however, are desirably of sizes to have the former extend a greater distance into the interior of the drum than the other rib.

14 represent bolts extending through flanges provided on the drum-head 6 and the ring 8 for securing the drum parts together.

The head 6 is provided with a concentric hub 6¹ for the end of a horizontal shaft 15 which is journaled in stationary bearing boxes 16. A pulley 17 is mounted on said shaft for rotating the drum, as by means of a driving belt.

Extending into the open end of the drum is a funnel-shaped distributer 18 terminat-

ing, preferably, in a plurality of blades 19 arranged as shown in Fig. 2, to provide intervening slots 20 through which material is delivered into the groove A. The smaller outer end of the distributer 18 is secured to a tubular shaft 21 which is mounted in journal bearings 22 of a frame 23. A spiral tube 24 is connected to the outer end of shaft 21 and when rotated with the shaft 65 serves to scoop the slime—that is to say, disintegrated ore or auriferous sands mixed with water—from a trough 25 and deliver the same into the hollow shaft 21. This trough and the frame 23 are supported upon a carriage 26 which is movable axially of the drum 5 upon track-rails, such as 27, to enable the distributer to be withdrawn from the drum when the latter is to be cleaned.

28 represents a pulley for a belt to rotate the shaft 21 together with the distributer 18 and the feeding scoop 24.

29 is an annular gutter inclosing the end of the drum and is provided with a spout 30 for discharging the refuse material from the drum into a waste trough 31. The gutter 29 is desirably connected to said carriage so as to be movable therewith into and out of operative position.

The inner surfaces of the annular plates 9 and 10 which form parts of the circular wall of the drum, are coated with mercury to constitute amalgam-plates. This mercury may be applied directly to such surfaces prior to operating the machine or may be supplied with the slime to be separated therefrom by its affinity for the copper during the progress of the work.

The operation of the invention is as follows: With the various parts of the machine occupying the relative positions in which they are illustrated in Fig. 1, the shafts 15 and 21 are driven to rotate the drum 5 and the distributer 18 together with the rotary scoop 24. When the scoop is thus actuated the auriferous material in the form of slime is taken up from the trough 25 into the hollow shaft 21 whence it is impelled to flow into the distributer 18. By reason of the conical shape of the latter it is evident that the circumferential speed thereof is greater at its discharge end than at its connection with the shaft, hence the centrifugal force increases in its effect upon the slime as it approaches the large end of the distributer. Accordingly, the slime is delivered into the

peripheral groove A of the drum in a series of relatively thin sheets through the interstices 20 between blades 19. The slime is thus supplied throughout the surface of the plate 9 whereupon the centrifugal force continuing to act, but somewhat more powerfully, causes the heavier portions of the slime to become interposed between the lighter portions of the slime and the mercury-covered surface of the plate 9. This revolving motion of the slime is, however, of less velocity than that of the plate by reason of an accumulation of the slime at the bottom or a tendency to that effect, due to the action of the force of gravity. Hence there is a certain amount of attrition between the heavier portions of the slime and the mercury to bring the latter into such intimate contact that the metals which have an affinity for the mercury are seized thereby to adhere to the wall part 9 in the form of an amalgam. The slime will, however, accumulate in the groove A until at the bottom its depth exceeds the effective height of the ridge 7¹ whereupon the lighter portions of the slime will overflow onto plate 10 in groove B where it is spread more thinly over the relatively large area of the plate; and whereby the particles of amalgamable substances in the slime which have escaped from the groove A are collected on the amalgamated surface. Eventually the refuse material is discharged over ridge 8¹ into gutter 29 to pass off by spout 30 and trough 31. The invention is found to be particularly useful in the treatment of "tailings" or material which has passed over the concentrating tables of a quartz mill as affording not only a great saving of gold which has hitherto been lost but by serving to recover comminuted mercury contained in such tailings.

What I claim, is—

1. In apparatus of the class described, a drum rotatable on a horizontal axis and having intermediate its length a cylindrical portion formed of an amalgamable material and circumferentially unobstructed, said drum being closed at one end and with an opening at the other end of less diameter than the aforesaid cylindrical portion, and means extending into the open end of the drum adapted to feed auriferous material directly to the inner peripheral surface of the drum, said means being at all times unconnected with respect to the drum and removable therefrom for cleaning the interior of the drum while the same is rotating or otherwise.
2. In apparatus of the class described, a drum rotatable upon a substantially horizontal axis, said drum being closed at one end and having a cylindrical portion

formed of an amalgamable material and circumferentially unobstructed, and means for feeding auriferous material into the drum, said means being adapted to be inserted into or removed from the drum through the open end of the latter and being likewise adjustable lengthwise of the drum while the same is rotating to deliver the material upon said cylindrical portion and at selected distances from the closed end of the drum.

3. In apparatus of the class described, a drum comprising a cylindrical portion open at one end, and a head rigidly secured to and serving to close the other end of the drum, a substantially horizontal power driven shaft secured at an end thereof to said head and supporting the drum thereat without extending through the latter, and material feeding devices movable longitudinally of the drum and serving independently of said head to feed material against the peripheral wall of the drum, such feeding devices being adapted to be inserted into or withdrawn through the open end of the drum, while the latter is rotating.

4. In apparatus of the class described, the combination with a rotary drum having a peripheral wall with a circular inner surface adapted to be amalgamated, a head closing one end of the drum, a peripheral rib extending into the open end of the drum, and a shaft secured to said head and supporting the drum, of devices for feeding the material to be treated into the drum, said devices comprising a funnel-shaped distributor, a hollow shaft secured thereto and serving as a conduit for the material, means to supply the material to such conduit, means to rotate the drum and means to rotate said distributor and the conduit together but independently of the drum.

5. In apparatus of the class described, the combination with a cylindrical drum having a closed end and an open end, and a horizontally disposed power driven shaft connected to the closed end but not extending into the drum, of a removable material feeder introduced into the drum from its open end and adapted to be positioned for delivering such material directly against the peripheral wall of the drum at selected distances from the closed end thereof, and an annular gutter surrounding the open end of the drum to receive the waste material discharged therefrom.

Signed at Seattle, Washington, this 2nd day of October, 1914.

JOHN T. VOIGT.
